April 23, 1831

Green B. Palmer, Brindleton, North Carolina.
Setter's Patent

Dated April 23^d 1831.

The schedule referred to in this Setter's Patent and making part of the same, containing a description in the words of the said Green B. Palmer himself of his improvement in the machine for separating gold from earth and other substances.

To all whom these presents shall come. Be it known that Green B. Palmer of Brindleton County of Burke and State of North Carolina has invented a new and improvement in the Rock and mineral plan for washing out gold from the sand, gravel, and mineral dust and other mineral and earthy substances, called the "Tinney" machine, which the following is a full and exact description of the invention and operation of said

machines) as a means of multiplying power (to meet)

(Shows a strong hull with rockhammers of strong plank, open at one end and enclosed at the other, eight feet long and four feet wide inside at the plate, sloped toward the top on each side so as to be wider at top, with perforated iron plates or scions in it seven feet long and four feet wide inside, lying in a horizontal position, but depressed toward the upper end of the vessel. Below the perforated iron plates is the cork with the sides thereof extended down eight or ten inches to a plank bottom with a strong block of solid wood the full width, depth and length of four feet, to come up even with the perforated iron plates, over which the rock, grass, etc., is to be off at the ground).

The perforated iron plates are made in forms of wood or metal four or more inches wide and six or eight long, and all are constructed so as to be removed, in or out of place, to fit nicely to the sides and ends and particularly to fit down in a shoulder orallet made in the side block at the bottom so that the upper surface of the iron of perforated iron plate and side block be even, and to rest with the edges on the iron plate below it. The bottom of the end part of the side block with the perforated iron plate to have the shoulder made by four marks on the centre or a pair of angle holes on line of fit at the junction of the bottom with the side block the end hole or holes being intended to carry off the water and be a vent from the back.
